UNITED STATES PATENT OFFICE.

MORTIMER NORDEN, OF NEW YORK, N. Y., ASSIGNOR OF ONE-HALF TO HIMSELF AND ONE-HALF TO SILAS HEINEMAN, OF NEW YORK, N. Y.

ILLUMINATED SIGN.

No. 912,721.

Specification of Letters Patent.

Patented Feb. 16, 1909.

Application filed September 19, 1903. Serial No. 458,835.

To all whom it may concern:

Be it known that I, MORTIMER NORDEN, a citizen of the United States, residing at the borough of Manhattan, city, county, and State of New York, have invented an Improvement in Illuminated Signs, of which the following is a specification.

My present invention relates to an illuminated sign and particularly to that class of signs which are electrically lighted and employed for display for advertising or other similar purposes.

I am aware that heretofore illuminated signs have been placed within an electrically lighted frame in such a manner as to throw the light against the sides of the devices such as letters for instance forming the sign, but I believe it is broadly new to provide an electrically lighted sign within an electrically lighted frame in such a manner that the light from the frame will be cast upon all parts of the sign, more particularly upon the bottom of the sign as well as upon the sides thereof, thereby giving the sign the appearance of standing out in a flood of light, which latter is the purpose of my invention.

In carrying out my invention I preferably employ a frame provided with series of lights arranged both exteriorly and interiorly thereof of, a back for the said frame, a sign or other device secured to and off-set from the said back within the said frame so that the light from the interior of the frame may be reflected entirely around the said sign, and electrical circuits to and from the various series of lights for completing the electric circuits therethrough.

In the drawing, Figure 1 is a front elevation of my improved illuminated sign. Fig. 2 is a cross section on line α , α , Fig. 1, and Fig. 3 is a diagrammatic view illustrating the electrical connections employed in the sign.

Referring particularly to the drawing, 10 45 designates a frame which is preferably hollow and may be made of sheet metal or suitable composition, or any other desired material. The front inner portion of this frame is beveled as indicated at 11 and the inner 50 edge portion 12 is preferably made parallel with the front or outer sides of the frame. Exteriorly the frame is arranged with a series of lamps indicated at 13, the sockets thereof being suitably secured in the corners

of the frame and intermediate of the corner 55 lamps I prefer to employ a series of lamps indicated at 14, sockets for which are also suitably secured in the exterior portion of the said frame. Within the hollow frame 10 and in suitably spaced positions, I employ a 60 series of brackets indicated at 15 and to each bracket 15, on the opposite sides thereof, are secured lamp sockets 16 17 which respectively are adapted to receive lamp bulbs 18 19. The lamps 18 may be made of one color 65 and form one series and the lamps 19 may be of another color and form another series.

20 indicates a back or support provided with a flange 21 adapted to fit within the opening in the rear of the frame 10 to fill 70 and close the same, and the back 20 may be secured in position by suitable catches 22 or otherwise. Secured to the back or support 20 I employ a sign device indicated at 23. As illustrated in the drawing this sign device 75 represents the letter H and is preferably made of sheet metal, but as will be understood this sign device may represent any desired character or characters, or design and may be made of any other suitable 80 material.

Within the sign device 23 I prefer to employ sockets 24 adapted to receive an electric lamp bulb 25 so that the sign device 85 may be separately and independently lighted. The sign device 23 is secured to the back or support 20 by means of bolts 26 and the spacing collars 27 intervening between the said back or support 20 and the rear or under surface of the sign device 23, so that 90 instead of resting flush against the back or support 20 the sign device is offset therefrom in order that the light from the lamps within the frame may be reflected not only against the sides of the device but entirely 95 beneath the same to produce the effect of the sign device floating in a flood of light. The frame 10 is provided in a suitable position with circuit switches 28 29 30 and 31.

As hereinbefore indicated, the lights of the 100 series arranged exteriorly of the frame and both of the sides arranged interiorly of the frame and the lights arranged in the sign device are preferably arranged to be turned on and off independently of one another, 105 and as shown in Fig. 3 the lead wires 32 are connected across the terminals of each of the said switches 28 29 30 and 31; the

wires 33 from the switch 28 carrying the current to one of the series of interiorly arranged lamps; the wires 34 from the switch 29 carrying the current to the other series of interiorly arranged lamps; the wires 35 from the switch 30 carrying the current to the lamps in the sign device 23, and the wires 36 carrying the current to the lamps arranged exteriorly of the frame, and as will be apparent, any one or more of these series of lamps may be turned on simultaneously and that any combination of the same may be employed.

I claim as my invention:

1. An illuminated sign comprising a hollow frame, series of electric lights arranged both exteriorly and interiorly thereof, a sign within the said frame, a support and means

for securing the said sign to the said support in an off-set position therefrom. 20

2. An illuminated sign comprising a hollow frame, a series of lights arranged exteriorly of the frame, independent series of lights arranged interiorly of the frame, a sign device within the said frame, lights in said sign device, a back for the said frame, means for securing the said sign device to the said back in an off-set position therefrom and independent electric circuits to each of the said series of lights. 25

Signed by me this 19th day of August 1908.

MORTIMER NORDEN.
